R. HOFFMAN

OIL STOVE

Original Filed July 19, 1919

Patented Feb. 12, 1924.

1,483,088

UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Original application filed July 19, 1919, Serial No. 311,953. Divided and this application filed January 3, 1921. Serial No. 434,497.

To all whom it may concern:

Be it known that I, RUDOLPH HOFFMAN, a citizen of the United States, residing at Kankakee, in the county of Kankakee and State of Illinois, have invented certain new and useful Improvements in Oil Stoves, of which the following is a specification.

The invention relates to oil stoves of the type embodying a constant-level oil supply 10 reservoir and one or more burners adapted to be raised and lowered with reference to said constant level whereby to control the flow of oil from the reservoir to the burners. Such burners are usually supported beneath 15 the stove top upon a horizontal stationary supply pipe, and to permit of the vertical movement of the burners with reference to said pipe an extensible pipe connection is employed between the burner and supply 20 pipe comprising two telescoping pipe sections.

Owing to the tendency of the oil to creep along a metallic surface by capillary attraction, I provide a liquid metallic seal of 25 mercury or the like for the joint between said pipe sections, which absolutely prevents the leakage of oil. One of the objects of this invention is to provide means of advantageous construction to form a closure 30 for retaining such mercury against escape when the stove is tipped up upon end or inverted as in shipping.

Another object of the invention is to provide improved means for effecting the raising and lowering movements of the burner with reference to the constant oil level.

In the accompanying drawings, I have illustrated a preferred form of my invention, another form being described and 40 claimed in my co-pending application Serial No. 311,953, filed July 19, 1919, of which this application is a division. Fig. 1 is a vertical sectional view taken on line 1—1 of Fig. 2. Fig. 2 is a top plan view of the 45 device shown in Fig. 1, but with the burner removed.

In the drawings 1 designates the bowl or trough of an oil burner mounted upon a stationary horizontal pipe 2 which receives 50 a supply of oil from a constant-level oil reservoir (not shown) of well-known construction. 3 indicates generally an extensible pipe connection between the trough 1 and pipe 2, by means of which a supply of oil

is conducted to the burner and maintained 55 at a constant level in a well-known manner.

The extensible connection 3 between the burner bowl or trough 1 of the burner and the supply or delivery pipe 2 comprises two sections 3^a and 3^b carried respectively by 60 the pipe 2 and trough 1. The inner section 3^a is made of a diameter slightly less than the diameter of the outer section 3^b and at its lower end is screw-threaded into a fitting 4 connected in a well-known manner to the 65 delivery pipe 2 so as to communicate therewith. The pipe section 3^b is rigid with the lower edge of the burner bowl 1, being secured thereto as by brazing, and is adapted to freely receive the section 3^a.

The means for clamping the fitting 4 upon the delivery pipe 1 so that it shall be capable of firmly supporting the burner in its proper position, comprises a pair of links 5 and 6 operatively engaging with 75 studs 7 and 8 upon opposite sides of the fitting and similarly connected to an intermediate block 9 below the pipe 2. Said block has a set screw 10 therein adapted to operatively engage with the pipe 2. By simply tightening said screw, the fitting 4 may be drawn downwardly onto the delivery pipe 2 and firmly clamped in position thereon.

For the purpose of providing an annular channel around the inner pipe section 3^a of 80 the extensible pipe connection 3, for the reception of a quantity of mercury or the like in which the lower end of the pipe section 3^b may be immersed, I provide a tubular stem or member 11 carried by the fitting 85 4. This member is in the form of a pipe of a diameter somewhat greater than the diameter of the pipe section 3^a and at its lower end is threaded into a socket 12 provided in the upper portion of the fitting 4. The 90 pipe section 3^a and the tubular member 11 are thus concentrically arranged and are spaced apart to form a channel 13. Said channel is filled with a sealing liquid such as mercury 14 to a depth sufficient to cover 95 the lower end of the outer pipe section 3^b in all operative positions of the latter relative thereto. It will be seen that oil standing in the pipe section 3^a and overflowing into the space between it and the section 3^b 100 is prevented from flowing around the lower end of the latter section by the mercury in the channel into which said section depends.

It will be seen that the annular channel 13 formed between the stem 11 and the inner pipe section 3^a is normally open in the operative position of the parts, so that if the stove 5 is tipped upon end or inverted, the mercury will escape from the channel unless prevented. In the present instance, to prevent such escape of the mercury the outer pipe section 3^b near its upper end is provided 10 upon its inner and outer sides with a pair of annular valve members 38 and 39 beveled at their lower ends and adapted to be seated upon correspondingly beveled edges of the inner pipe section 3^a and the stem 11.

15 As a means for locking said valve members in their operative or closed position at the upper end of the channel 13, a locking sleeve 40 and lock-nut 41 may be provided. The sleeve at its upper end is rigid 20 with the outer valve member 38 and at its lower end is provided with an annular shoulder 42 adapted to be engaged by the lock-nut 41, which latter is arranged to be screw-threaded onto the upper end of the 25 fitting 4. If desired, the lock nut may be provided with a pair of radially projecting pins 43 to facilitate the manipulation thereof. When the parts are in position to permit the raising and lowering of the burner, 30 the lock-nut rests loosely upon the upper end of the fitting 4^a, in the position shown in full lines in Fig. 8, and when it is desired to lock the valve members upon their seats 35 it is only necessary to screw the lock-nut 41 downwardly into the fitting, into the position shown in dotted lines in said figure. In this latter operation it will be seen that 40 the valve members may be firmly drawn downwardly upon their seats to close the upper end of the annular channel 13.

The raising and lowering means in the present instance, comprises a lever 44 pivoted between its ends on the upper end of the locking sleeve 40 and fulcrumed at its 45 inner or rear end upon a bracket 45 rising upwardly and rearwardly from the fitting 4. The lever 44 may comprise a pair of arms 44^a bent so as to form a hand portion 44^b at its forward end and to straddle the sleeve 40 (Fig. 2) rearwardly of said hand portion. A pair of oppositely extending pins 46 may be provided upon the upper end 50 of the sleeve 40 to form a pivotal mounting for each of the arms 44^a. At their rear ends 55 said arms are made of substantial width, substantially boot-shaped, and are provided with slots 47 for receiving pivots 48 mounted upon the rear end of the bracket. Said bracket at its forward end may be fixed 60 upon a collar 49 screw-threaded onto the fitting 4, and at its upper rear end, the bracket may be provided with a pair of up-standing lugs 50 at the opposite edges thereof for supporting the pivots 48. Said pivots 65 may be in the form of screws having nuts

48^a and lock-nuts 48^b. As the hand portion 44^b of the lever is raised and lowered, the lever carrying with it the burner trough 1, pins 46 and the inner or rear ends of the arms 44^a move forwardly and rearwardly 70 to the extent determined by the length of the slots 47. The lock nuts 48^b serve to hold the nuts 48^a properly adjusted to effect a frictional engagement between the 75 relatively sliding parts whereby to retard the lowering movement of the burner.

It will be seen that I have provided in 80 an oil stove employing mercury or the like for preventing the leakage of oil past the joint between the pipe sections of the extensible pipe connection, means of advantageous construction for retaining the liquid when the stove is inverted, as in shipment. The raising and lowering means for the burners are also advantageous, being simple in construction and easily operable to effect the 85 raising and lowering movement of the burners as may be desired. Claims directed to the mercury seal per se are contained in my co-pending application Serial No. 308-, 90 542, filed July 3, 1919.

While I have herein illustrated and described the invention with considerable particularity, I desire to have it understood that 95 in the interpretation of the appended claims they are not to be limited except as may be necessitated by the state of the prior art.

I claim as my invention:

1. In an oil stove, the combination with 100 an oil supply pipe and a burner, of a fitting mounted on said supply pipe, an extensible pipe connection between said fitting and said burner comprising an inner pipe section rising from the fitting, an outer section depending from the burner and telescoping 105 over the inner pipe section, a tubular stem providing an annular channel around said inner pipe section for the reception of a quantity of mercury or the like into which the lower end of the outer pipe section is immersed, a pair of valve members upon said outer pipe section adapted to be seated upon the upper ends of said inner pipe section, a stem to form a closure for said annular channel, a locking sleeve rigid with said outer pipe section and surrounding said stem, said sleeve having at its lower end a shoulder, a lock-nut engaging said shoulder and said fitting to draw said sleeve downwardly and clamp said valve members upon their seats, and raising and lowering means for the burner comprising a bracket carried by said fitting, and a lever fulcrumed on said bracket and pivotally connected to said locking sleeve. 110

2. In an oil stove, the combination with 115 an oil supply pipe and a burner mounted for movement with reference to said pipe, of an extensible pipe connection between said pipe and said burner comprising a pair 120

of telescoping pipe sections, a tubular stem forming with the inner pipe section an annular channel for the reception of a metallic liquid seal into which the lower end of the outer pipe section is adapted to be immersed, and means for closing the upper end of said channel including a valve member rigid with the outer pipe section and adapted to be seated upon the upper end of 10 said stem, a locking sleeve rigid with said outer pipe section and surrounding said stem, a part rigid with the inner pipe section and arranged coaxially thereof, and a lock nut operatively engaging with said sleeve and said part to clamp said valve member to its seat.

3. In an oil stove, the combination with a burner and a source of oil supply, of means for raising and lowering the burner, means 20 for conducting a supply of oil from said source of supply to the burner but permitting of its vertical movement, said means comprising a sectional pipe having a sliding joint, means providing an annular channel for the reception of mercury to seal said joint, and means for closing said annular channel comprising a valve member, a locking sleeve surrounding said pipe and rigid with said valve member, and means cooperating with said sleeve to force said valve member downwardly upon its seat.

4. In an oil stove, the combination with an oil burner and an oil supply pipe, of means for conducting a supply of oil from 30 said pipe to the burner but permitting of the vertical movement of the latter, said means comprising a sectional pipe having a sliding joint, means providing an annular channel around said joint for the reception 40 of mercury or the like for sealing the joint; and means for closing said channel comprising a valve member, a part rigid with the supply pipe, and a lock nut operatively connected with said valve member and adapted to operatively engage with said part.

5. In an oil stove, the combination with a burner and an oil supply pipe, of means for conducting a supply of oil from said pipe to said burner but permitting of a vertical 50 movement of the latter, said means comprising a sectional pipe having a sliding joint, means providing a chamber open at its upper end for the reception of mercury adapted to seal said joint, and means for closing 55 said chamber comprising a valve member, a locking sleeve rigid with said valve member and surrounding said sectional pipe, a stationary part and a lock-nut for connecting said sleeve to said stationary part whereby 60 to clamp said valve member upon its seat.

6. In an oil stove, the combination with a vertically movable burner and an oil supply pipe, of an extensible pipe connection between said burner and supply pipe including a pair of relatively slideable pipe sec-

tions, an upright bracket, a member rigid with said burner, and guided by said extensible pipe for vertical movement with the burner, and a lever fulcrumed on said bracket and pivoted between its ends to said 70 vertically movable member.

7. In an oil stove, the combination with an oil supply pipe and a burner, of means for conducting a supply of oil to said burner but permitting of the vertical movement of 75 the latter, and raising and lowering means for the burner comprising a bracket, a part depending from the burner and rigid therewith, and a lever pivotally connected between its ends to said pendant part of the 80 burner and fulcrumed on said bracket.

8. In an oil stove, the combination with a burner and an oil supply pipe, of an extensible pipe connection between said burner and said pipe comprising a pair of telescoping pipe sections, a stationary upright bracket having a pivot at its upper end, and a lever pivotally connected with said burner and having a slot at its free end in which the pivot on said bracket slidably engages. 85

9. In an oil stove, the combination with an oil supply pipe and a burner of a fitting mounted on said pipe, an extensible pipe connection between said fitting and said burner comprising an inner pipe section rising from the fitting and an outer telescoping pipe section depending from the burner, and means for raising and lowering the burner comprising a hand lever pivotally mounted with reference to said fitting and 95 pivotally connected between its ends with said burner. 100

10. In an oil stove, the combination with an oil supply pipe and a burner, of an extensible pipe connection between said supply pipe and said burner comprising a pair of telescoping pipe sections, an upwardly and rearwardly inclined bracket supported by said supply pipe, and a hand lever pivotally mounted on said bracket and extending forwardly for connection with said burner. 105

11. In an oil stove, the combination with an oil supply pipe and a burner, of an extensible pipe connection between said supply pipe and said burner comprising a pair of telescoping pipe sections, a stationary bracket, a lever pivotally mounted on said bracket, a part rigid with said burner and having the lever pivotally connected therewith whereby an operation of the lever will 115 raise and lower the burner, and means carried by the bracket adapted to frictionally engage the lever to retard the lowering movement of the burner. 120

12. In an oil stove, the combination with an oil supply pipe and a burner, of means for raising and lowering the burner with reference to said supply pipe, and means for conducting a supply of oil from the supply pipe to the burner, said raising and lower- 125 130

ing means comprising a bracket mounted upon the supply pipe and projecting rearwardly and upwardly from its support, and a hand lever pivotally mounted on the bracket to swing in a vertical plane and having a forwardly extending portion operatively connected with the burner.

13. In an oil stove, the combination with an oil supply pipe, of a burner mounted for movement up and down with reference to said pipe, and means for raising and lowering the burner comprising a bracket mounted upon the pipe and a lever pivotally mounted with reference to the burner and fulcrumed on said bracket, said lever being movable longitudinally relative to its fulcrumed pivot.

14. In an oil stove, the combination with an oil supply pipe and a burner, of means for conducting a supply of oil to the burner but permitting a raising and lowering thereof, and means for effecting such raising and lowering movements comprising a lever, a stationary bracket upon which said lever is fulcrumed to swing on a horizontal axis, and means pivotally connecting the lever between its ends with the burner.

15. In an oil stove, the combination with an oil supply pipe and a burner, of means for raising and lowering the burner relative to said pipe, and means for conducting a supply of oil from the pipe to the burner, said raising and lowering means comprising a lever pivotally connected with said burner, a stationary bracket having a pivot, said lever having a slot for receiving said pivot, and means for frictionally engaging the lever on its opposite sides, to retard the lowering movement of the burner.

16. In an oil stove, the combination of a burner and an oil supply pipe, means for conducting a supply of oil from said pipe to said burner comprising a sectional pipe having a sliding joint, means providing a chamber open at its upper end for the reception of mercury adapted to seal said joint, a part rigid with the burner, a bracket fixed with reference to said supply pipe, a lever fulcrumed on said bracket and pivoted to said part on the burner, valve means carried by said bracket operable in the movements of the burner into engagement with the upper end of said chamber so as to close it, and means for locking said valve means in its closed position.

17. In an oil stove, the combination of a burner and an oil supply pipe, means for conducting a supply of oil from said pipe to said burner comprising a sectional pipe having a sliding joint, means providing a chamber open at its upper end for the reception of mercury adapted to seal said joint, a part rigid with the burner, a bracket fixed with reference to said supply pipe, a lever fulcrumed on said bracket and pivoted to said

part on the burner, valve means carried by said bracket operable in the movements of the burner into engagement with the upper end of said chamber so as to close it, and means for locking said valve means in its closed position, the last mentioned means comprising a lock-nut adapted to operatively engage said depending part of the burner and having a screw-threaded engagement with a stationary part on the supply pipe.

18. In an oil stove, the combination of an oil supply pipe, a burner, an extensible connection between said pipe and said burner permitting of the up and down movements of the latter and comprising a pair of telescoping pipe sections, means providing an annular chamber for the reception of a quantity of mercury or the like in which the free end of the outer pipe section is adapted to be immersed, means for raising and lowering the burner, valve means adapted to close the upper end of said channel, and means independent of the raising and lowering means for locking said valve means in closed position.

19. The combination of a supply pipe, a burner, an extensible connection between said pipe and burner comprising a pair of telescoping pipe sections, means providing an annular channel for the reception of a quantity of mercury into which the free end of the outer one of said pipe sections is adapted to be immersed, valve means for closing the upper end of said channel, a sleeve rigid with said valve means and surrounding said extensible connection, and means including a nut loose on said sleeve to clamp said valve means in its closed position.

20. The combination of an oil supply pipe having a fitting thereon, a burner, an extensible pipe connection between said fitting and said burner, means providing a metallic liquid seal for the extensible pipe connection including a chamber open at its upper end, valve means for closing said chamber, a member fixed with reference to said valve means, and a lock-nut adapted slidably to engage said member to secure it to said fitting and thereby said valve means in its closed position.

21. In an oil stove, the combination of a burner, means including an extensible pipe connection for conducting a supply of oil to the burner, means for raising and lowering the burner as permitted by said pipe connection, and means independent of the raising and lowering means for locking the burner in its lowermost position.

22. In an oil stove, the combination with an oil supply pipe and a burner, of means for conducting a supply of oil to the burner but permitting the raising and lowering thereof, and means for effecting such rais-

- ing and lowering movements comprising a stationary bracket, a lever operatively connected with said burner and with said bracket, and means at the rear end of said 5 lever adapted to engage frictionally therewith so as to retard the lowering movement of the burner.
23. In an oil stove, the combination with an oil supply pipe and a burner, of means 10 for conducting a supply of oil to the burner but permitting the raising and lowering thereof, and means for effecting such raising and lowering movements comprising a stationary bracket and a lever operatively 15 connected with the burner and with said bracket, one of said operative connections including a slot and pivot and means for retarding the lowering movements of the burner.
24. In an oil stove, the combination with an oil supply pipe and a burner, of means 20
- for conducting a supply of oil to the burner but permitting the raising and lowering thereof, and means for effecting such raising and lowering movements comprising a stationary support and a lever operatively 25 connected with the burner and with the support, one end of said lever being bifurcated to form spaced arms, and means frictionally engaging with said arms whereby to retard 30 the lowering movements of the burner.
25. In an oil stove, the combination of a burner, and means for raising and lowering the burner including a bracket having a pair of lugs spaced apart, and a lever 35 operatively connected with said bracket and having arms frictionally engaging with said lugs whereby to retard relative movement between the lever and said bracket.

In testimony whereof I have hereunto set 40
my hand.

RUDOLPH HOFFMAN.
